UNITED STATES PATENT OFFICE.

CHARLES E. EGAN, OF CHARLESTON, WEST VIRGINIA, ASSIGNOR OF ONE-THIRD TO
ELLET S. BAUMGARTNER, OF MORGANTOWN, WEST VIRGINIA, AND ONE-THIRD TO
CHARLES A. SEMBOWER, OF CLARKSBURG, WEST VIRGINIA.

AUTOMATIC ALARM.

1,178,387.

Specification of Letters Patent.

Patented Apr. 4, 1916.

Application filed June 17, 1915. Serial No. 34,699.

To all whom it may concern:

Be it known that I, CHARLES E. EGAN, a citizen of the United States, residing at Charleston, in the county of Kanawha and 5 State of West Virginia, have invented certain new and useful Improvements in Automatic Alarms; and I do declare the following to be a full, clear, and exact description of the invention, such as will enable others skilled in the art to which it 10 pertains to make and use the same.

This invention relates to alarms thermally controlled.

The principal object of this invention is 15 the provision of a thermostatically controlled alarm which will be particularly advantageous to pomologists and florists to warn them in the event of any sudden temperature drop so that damage to the fruit 20 or flowers may thus be prevented.

Another and further object is to provide a spring actuated member in connection with a thermostat which normally is inoperatively disposed but when the temperature 25 drops to a predetermined point, is released to actuate the alarm with which it is operatively connected.

Another and further object is to provide a novel and efficient means wherein said 30 alarm may be released at a predetermined temperature.

Another and further object is to provide a thermally controlled alarm of the character enumerated which is simple, efficient and 35 one that may be readily and conveniently installed.

With these and other objects in view the invention consists in certain novel details of construction, combination and arrangement 40 of parts as will be more particularly hereinafter set forth and claimed.

In the accompanying drawings in which corresponding parts are indicated by similar reference characters: Figure 1 is a top 45 plan view of the alarm casing and thermostat mechanism diagrammatically illustrated, the latter as operatively arranged with respect to the former; Fig. 2 is a front elevation of an alarm casing and thermo- 50 stat mechanism illustrating diagrammatically the relative arrangement of the latter with respect to the former when operatively associated; Fig. 3 is a top plan view of the

casing and thermostat mechanism, the cover of the casing being removed, and that of the 55 thermostat being removed; Fig. 4 is a longitudinal section taken on the line 4—4 of Fig. 3; Fig. 5 is a transverse section taken on the line 5—5 of Fig. 3; Fig. 6 is a similar view taken on the line 6—6 of Fig. 7; Fig. 60 7 is a horizontal section taken on the line 7—7 of Fig. 6; Fig. 8 is a transverse longitudinal section taken on the line 8—8 of Fig. 3; Fig. 9 is a detail rear elevation of the thermostatic mechanism to illustrate 65 more clearly the pointer and calibrations arranged on the back of said mechanism.

Owing to the irreparable damage sometimes worked upon flowers, fruits and the like by sudden and unexpected fall in temperature I propose to provide a thermostatically controlled alarm which is to be situated in the bed-room of those whose duties compel attendance to such matters, so that they may be warned in time and thus 70 avert the damage which would otherwise result. This alarm consists of a clock mechanism 1, the latter including an escapement wheel 2, a spring 3 and gears 4 controlled by said spring and co-operating with said 75 escapement wheel to actuate the latter. The spring 3 is mounted upon an arbor 4' to one end of which is secured an operating knob 5. An escapement 6 carrying a clapper 7 80 co-acts in the customary manner with the escapement wheel 2 as will be readily understood without further description.

The foregoing mechanism is suitably housed in a frame 8 consisting of upper and lower suitably spaced plates 9 and 10 respectively. The lower plate 10 carries the laterally projecting feet 11 which are apertured to receive suitable fastening elements. Loosely mounted upon the arbor 4 intermediate the operating knob thereon and upper plate 9 is a bell crank 12. This crank 12 has one leg thereof provided with a laterally projecting finger 12' adapted to engage the curved extension 13 formed on the escapement shaft whereby the clapper 7 is 90 maintained in a fixed position. Under ordinary conditions the alarm is inoperative. The bell crank 11 which it will be seen performs the functions of a trigger has an aperture 14 formed in the other leg thereof 95 for a purpose to be hereinafter set forth. An 100 105

alarm bell 15 is suitably secured in juxtaposition with respect to the clapper 7 so that when the latter operates it will sound the bell and thus give the desired alarm. The foregoing alarm structure is inclosed in a housing 16 which may be placed in any desired position in the bedroom of the party to be warned. Of course, however, it is to be understood that this alarm may be 10 mounted in any manner best suited to circumstances and conditions.

To enable the bell 15 to be sounded when the temperature falls below a predetermined degree, I provide a thermostat 16' operatively connected with the hereinbefore mentioned bell crank 12 to actuate the latter and release the escapement mechanism in a manner hereinafter to be set forth. This thermostat consists of an annular casing 17 20 having one end open as at 18 and the other end closed by an end plate 18'. A cover 19 telescopically engages the free edge of the casing 17 and has its flange partially cut away to form a peripheral slot 19' for a purpose hereinafter to be set forth. A spider 20 extends diametrically across the open end of casing 17 and has one extremity thereof extended and laterally offset to form a foot 21, the latter being apertured as at 25 22 to receive suitable fastening elements by means of which the casing may be properly supported upon any suitable standard.

An annular plate 23 having a laterally extending peripheral flange 24 to the free edge 35 of which is secured a diaphragm 25 is positioned within the casing intermediate the closed end of the latter and spider 20 as clearly shown in Figs. 5 and 6 of the drawings. The diaphragm 25 is secured to the 40 flange 24 in such a manner as to absolutely exclude ingress of air to the chamber 26 thus formed. By constructing an air-tight chamber in the manner aforesaid it will be obvious that the latter will contract and expand in accordance with the contractile and expanding action of the medium inclosed therein. Concentrically secured to the diaphragm 25 and extending laterally therefrom is an externally threaded pin 27 which 45 latter is adapted to project through the opening 28 concentrically formed in end plate 18'. A spring 29 encircles the pin 27 and is interposed between the inner surface of the end plate 18' and the diaphragm 25. An adjusting nut 30 is engaged with the 55 free end of pin 27 and enables the diaphragm 25 to be placed under more or less tension as desired dependent upon the temperature at which the thermostat is desired 60 to operate. The nut 30 may be formed with a pin at 31 the lower end of which coats with the calibration formed on the outer surface of end plate 18' as will be readily understood without further description.

65 The plate 23 of chamber 26 has concen-

trically affixed thereto by solder or otherwise an annular laterally projecting stud 32 which latter is adapted to project through the annular opening 33 formed in spider 20 coincident with the axis of chamber 17. 70 This stud 32 normally projects above the upper surface of the spider 20 and performs the functions of a stop for a purpose hereinafter to be set forth. A lever 34 is pivotally connected at one end to the spider 20 75 contiguous one extremity thereof as clearly shown in Figs. 5 and 7 of the drawings. An apertured anchorage 35 is formed on the edge of the lever 34 in annular relation with respect thereto and engages one end of 80 a coil spring 36 the other end of which is secured to an apertured lug 37 formed on spider 20 adjacent the pivotal end of lever 34. As the spring 36 has a tendency to elevate lever 34 I find it expedient to provide 85 a U-shaped guiding plate 38 which is integrally formed on the longitudinal edge of the spider 20 adjacent the opening therein so that when the lever 34 is disposed in its inoperative position the lower surface thereof will be maintained in contact with the upper surface of spider 20 as will be readily understood without further description. The U-shaped guiding plate 38 has its free 90 edge beveled to coöperate with the beveled 95 portion 39 of lever 34 for obvious reasons.

From the foregoing structure it will be seen that as the lever 34 is forced intermediate the lower surface of the guiding plate 38 and the upper surface of the spider 20 100 the pin 32 of the diaphragm 25 will be depressed to be released however as soon as the lever 34 has been properly disposed beneath guiding plate 38 since the aforesaid pin 32 is normally disposed in the path of lever 34 the same will be retained in an inoperative position until the pin is depressed which latter can only occur when the chamber 25 contracts.

The free end of lever 34 is apertured as 110 at 40 to receive one end of a wire 41 the other extremity of which is passed through an aperture 42 in the housing 16. The free end of said wire is then fastened to the apertured leg of bell crank 12 by means of the 115 opening therein. This arrangement operatively connects the bell crank or trigger 12 with lever 34 so that the former and latter will be simultaneously operated.

The thermostat above described may be 120 mounted at a point wherein it is exposed to the elements and would be readily influenced by temperature changes. In this connection it is to be noted that inasmuch as the wire 41 must extend from the alarm located in 125 the bedroom to the thermostat situated on the exterior of said room, an opening may be formed in the window sash to accommodate the passage of said wire as will be readily understood without further description. 130

When the cover 19 is properly positioned upon casing 17 the cutaway portion of this flange will permit the free end of the lever 34 to project to the exterior of said casing 5 and at the same time allow horizontal movement on the part of said lever. In this connection it is to be noted that in order to limit the outward movement of the lever 34 there is provided a stop 43 formed on spider 20 adjacent the pivoted end of lever 34 as will be readily seen upon reference to Fig. 7 of the drawings.

In view of the above structural outline it will be at once apparent that if the thermostat is standardized to operate at a predetermined temperature, when said temperature is reached the chamber 26 will contract thus withdrawing the pin 32 from the path of lever 34 and allowing the spring 36 to 20 retract said lever. As the lever 34 is retracted it will actuate wire 41 and cause the latter to operate bell crank 12 and disengage the finger 12' thereof from the curved extension on the escapement shaft so that the 25 clock mechanism is thus free to actuate the clapper and sound the bell which will accordingly warn the pomologist or florist in time to prevent serious injury to the fruit or flowers as the case might be. Therefore in 30 the light of the above it will be seen that I have provided a thermostatically controlled alarm which is simple, efficient in operation, and absolutely dependable, as well as one that may be quickly and readily installed 35 and removed whenever and wherever necessary.

Although in the foregoing I have set forth certain elements best adapted to perform the functions allotted to them nevertheless it will 40 be understood that various changes as to form, substance, etc., may be resorted to within the scope of the appended claims without departing from or sacrificing any of the principles of the invention.

45 I claim:

1. In a thermostat a pivotally mounted lever, a thermally controlled expansible and contractible member, a stop connected with said member and adapted to project in the 50 path of said lever when the thermally controlled member is expanded to releasably maintain the lever in inoperative position, said stop being movable out of the path of said lever when said member is contracted, 55 and a retractile spring in connection with said lever to retract it on the release thereof.

2. In a thermostat, a casing, a spider carried thereby and having an opening therein, a stop slidably mounted in said opening, a thermally controlled expansible and contractible member connected to actuate said stop, a pivotally mounted lever carried by said spider, said stop being adapted to project into the path of said lever to 60 releasably maintain it in inoperative position,

and a spring in connection with said lever to retract it upon the withdrawal of said stop.

3. In a thermostat, a casing having one end open, a spider extending across the open end of said casing and having an opening therein, a thermally controlled expansible and contractible member disposed within said casing, a stop slidably mounted in said opening and operatively connected with said thermally controlled member, a lever pivotally connected at one extremity to said spider, said stop being normally projected in the path of said lever to releasably connect the same in inoperative position, and a retractile spring connecting said lever with said spider whereby the former is actuated on withdrawal of said stop. 70 75

4. In a thermostat, a casing having one end open, a spider extending across the open end of said casing and having an opening therein, a thermally controlled expansible and contractible member situated in said casing beneath said spider, a stop slidably mounted in said opening and connected with said expansible and contractible member, said stop projecting in the path of said lever to releasably maintain the latter in inoperative position, a guiding plate in connection with said spider to retain said lever when the lever is inoperatively disposed, and a retractile spring having one end connected with said lever and the other end connected with said spider whereby to retract said lever on withdrawal of said stop. 80 85 90 95 100

5. In a thermostat, an annular casing open at one end, a spider disposed diametrically across the open end of said casing, and having an opening therein, an annular plate mounted within said casing beneath said spider, a rearwardly projecting peripheral flange formed on said plate, an expansible and contractible diaphragm affixed to the free end of said flange, an externally threaded pin carried by said diaphragm and projecting through a concentric opening formed in said casing, a spring interposed between said casing and diaphragm, an adjusting nut on the free end of said pin, whereby to adjust the tension of said diaphragm, a stop slidably mounted in the opening in said spider and having one end connected with said plate, a lever pivotally mounted on said spider and movable horizontally thereover, said stop normally projecting in the path of said lever to normally maintain the same in operative position, and a spring connection between said lever and spider to retract the former upon withdrawal of said stop. 105 110 115 120 125

6. In a thermostat, an annular casing open at one end, a spider disposed diametrically across the open end of said casing, and having therein an opening, an annular plate mounted within said casing beneath said 130

spider, a rearwardly projecting peripheral flange formed on said plate, an expansible and contractible diaphragm affixed to the free end of said flange, an externally threaded pin carried by said diaphragm and projecting through a concentric opening formed in said casing, a spring interposed between said casing and diaphragm, an adjusting nut on the free end of said pin whereby to adjust the tension of said diaphragm, a stop slidably mounted in the opening in said spider and having one end connected with said plate, a lever pivotally mounted on said spider and movable horizontally thereover, said stop normally projecting in the path of said lever to normally maintain the same in operative position, a guide plate formed on one edge of said spider, and adapted to engage said lever when the latter is in inoperative position, and a spring connection between said lever and spider to retract the former upon withdrawal of said stop.

7. A device of the character described comprising an annular casing having one end open, a spider disposed upon the open end of said casing and extending diametrically thereacross, said spider having therein an opening, an annular plate situated in said casing beneath said spider, said plate having a rearwardly extending peripheral flange, an expansible and contractible diaphragm affixed to the free edge of said flange, an externally threaded pin formed on and laterally projecting from said diaphragm, and through an opening formed in said casing, a spring enveloping said pin and interposed between the casing and diaphragm, an adjusting nut engaged with the free end of said pin whereby to adjust the tension of said diaphragm, a laterally projecting stop formed on said plate, a lever pivotally connected to said spider and movable horizontally thereover, said stop projecting through

the opening in said spider and into the path of said lever to releasably maintain the latter in inoperative position, a U-shaped plate formed on one edge of said spider to engage said lever when the latter is inoperatively disposed, a spring connection between said lever and spider to retract the former upon withdrawal of said stop, and a closure for the open end of said casing.

8. In a thermostat the combination of a casing, a cover telescopically engaged therewith and having a peripheral slot therein, a spider mounted in said casing and extending transversely thereacross and projecting through the slot in the cover thereof, the projecting end of said spider being offset and apertured to form a support engaging foot, a thermally controlled expansible and contractible member mounted in said casing below said spider and having an outwardly extending pin therein projectable through an opening in said spider, a lever pivoted at one end on said spider and movable horizontally thereover, said pin being projectable into the path of said lever on the expansion of said thermally controlled member for holding said lever in retracted position, a guide plate carried by said spider for engagement with said lever, a stop carried by said spider to limit the movement of said lever in one direction, and a coiled spring connected with one edge of said lever and with said spider and adapted to move said lever away from said guide plate when said pin is moved out of the path of the lever on the contraction of said thermally controlled member.

In testimony whereof I have hereunto set my hand in presence of two subscribing witnesses.
